CLAIM

The ornamental design for leggings, as shown and described.

DESCRIPTION

FIG. 1 is a rear perspective view of leggings according to our new design;

FIG. 2 is a front perspective view thereof;

FIG. 3 is a front elevation view thereof;

FIG. 4 is a rear elevation view thereof; and,

FIG. 5 is a right side elevation view thereof, the left side being a mirror image thereof.

The broken lines shown in the drawings are for the purpose of illustrating portions of the leggings that form no part of the claimed design.
